US00D492661S1

(12) **United States Design Patent** (10) Patent No.: **US D492,661 S**
Masamitsu et al. (45) Date of Patent: **** Jul. 6, 2004**

(54) **DISC PLAYER/RECORDER**

(75) Inventors: **Satoshi Masamitsu**, Tokyo (JP);
Gisuke Ota, Chiba (JP)

(73) Assignee: **Sony Corporation**, Tokyo (JP)

(**) Term: **14 Years**

(21) Appl. No.: **29/187,146**

(22) Filed: **Jul. 29, 2003**

(51) LOC (7) Cl. **14-01**

(52) U.S. Cl. **D14/156**

(58) Field of Search D14/135-136,
D14/156-157, 160-165, 167-168, 188,
193-198, 351; 369/75.1, 75.2, 77.1, 77.2;
455/344, 347-351
